UNITED STATES PATENT OFFICE.

FRANK MICHELBACH, OF DEL RAY, VIRGINIA.

DESIGN FOR A RUG-DISPLAY RACK.

Application filed January 9, 1923. Serial No. 4,840. Term of patent 7 years.

To all whom it may concern:

Be it known that I, FRANK MICHELBACH, a citizen of the United States, residing at Del Ray, in the county of Arlington and State of Virginia, have invented a new, original, and ornamental Design for Rug-Display Racks, of which the following is a specification, reference being had to the accompanying drawing, forming part thereof.

The figure is a perspective view of a rug display rack showing my new design.

I claim:

The ornamental design for a rug display rack as shown.

FRANK MICHELBACH.
